[57] CLAIM

The ornamental design for a slide support for a chiropractic table, as shown and described.

DESCRIPTION

FIG. 1 is a bottom perspective view of the slide support for a chiropractic table showing my new design;
FIG. 2 is a bottom plan view thereof;
FIG. 3 is a top plan view thereof;
FIG. 4 is a side view thereof, the opposite side appearing the same; and
FIG. 5 is an end view thereof, the opposite end appearing the same.
